US00D609362S

(12) **United States Design Patent**
Rannikko et al.

(10) **Patent No.:** **US D609,362 S**
(45) **Date of Patent:** **** Feb. 2, 2010**

(54) **CONTROL SOLUTION CONTAINER**

(75) Inventors: **Minna A. Rannikko**, Millbury, MA (US); **Thomas M. Pizza**, Dracut, MA (US); **Edelizete S. Pauplis**, Winchendon, MA (US); **Randy H. Byrd**, Pepperell, MA (US)

(73) Assignee: **Bionostics, Inc.**, Devens, MA (US)

(**) Term: **14 Years**

(21) Appl. No.: **29/325,539**

(22) Filed: **Oct. 2, 2008**

Related U.S. Application Data

(63) Continuation of application No. 11/756,716, filed on Jun. 1, 2007, which is a continuation-in-part of application No. 11/121,592, filed on May 4, 2005, now abandoned.

FOREIGN PATENT DOCUMENTS

WO WO 02 100265 12/2002

Primary Examiner—T. Chase Nelson*Assistant Examiner*—Anhdao Doan(74) *Attorney, Agent, or Firm*—McDermott Will & Emery LLP(57) **CLAIM**

The ornamental design for a control solution container, as shown and described.

DESCRIPTION

FIG. 1 is a top view of a control solution container, showing the new design, where the broken line represents a perforation, not environmental structure;

FIG. 2 is a side view of FIG. 1; and,

FIG. 3 is a bottom view of FIG. 1.
